Inventor
George A. Pennoyer
By *Lawrence L. Sargent* Attorney

UNITED STATES PATENT OFFICE.

GEORGE A. PENNOYER, OF CROWHEART, WYOMING.

HAY LOADER.

Application filed May 17, 1922. Serial No. 561,729.

To all whom it may concern:

Be it known that I, GEORGE A. PENNOYER, a citizen of the United States, residing at Crowheart, in the county of Fremont and 5 State of Wyoming, have invented a new and useful Hay Loader, of which the following is a specification.

The object of my invention is to provide an improved hay loader having the novel 10 combination and arrangement of parts disclosed in the accompanying drawings and hereinafter described. I attain these and other objects of my invention by the mechanism illustrated in the drawings, in which:—

15 Figure 1 is a side elevation of the invention.

Fig. 2 is a horizontal section approximately on line 2—2 of Fig. 1.

Referring to the accompanying drawings, 20 I provide a suitable mast 1 consisting of a suitable iron pipe, the lower end of which is sunk in the earth and the upper end secured in upright position by a suitable number of guy ropes 21. Vertically slidable on 25 pipe 1 I provide a loosely mounted clamp 3 to which is pivotally attached a suitable boom 2. Boom 2 is supported at the desired height by cable 6 which is run over pulley 7 carried by a suitable clamp 8 attached to the upper end of the mast. Cable 20 is divided and attached to fixed eyes 5 and 4 secured to the end and central portions of the boom, respectively, as shown in Fig. 1. The mast also carries a clamp 13 secured to 35 its upper end which supports a pulley 12 over which is run the operating cable 9, which is also run over the pulley 10 at the lower end of the mast, the pulley 10 being attached to a suitable clamp 11. Cable 9 is 40 run over a pulley 14 which is suspended from the slideable ring 15 on boom 2. The end of cable 9 carries a suitable hook or other means for engaging the hay to be loaded. Pivotally attached to ring 15 is a suitable latch 45 16 adapted to releasably engage the free end of the boom 2. The latch 16 is normally held in engagement with the boom by a suitable spring 18, as shown in Fig. 1. I provide a hand rope 19 attached 50 to the pivoted latch 16 by which the latch may be disengaged from the end of boom 2, to allow the ring 15 to slide away from the end of the boom toward the mast.

In operating the device, a horse, team or 55 mechanical power means may be attached to

the lower end of cable 9 to elevate and lower its hook 20, to which the hay to be loaded is attached by suitable means. The hand rope 19 is manually operated to release latch 16 from engagement with the end of boom 60 2 at the appropriate times. The latch 16 is a spring latch having its hooked end normally in engagement with the open end of the pipe boom 2. When the hand rope 19 is pulled downward it thereby disengages 65 the hooked end of the latch 16 from the boom and permits the ring 15 to slide inwardly on boom 2 and accordingly shift the position of hook 20 to which the material to be hoisted is attached. This arrangement permits of a wider range of operation of the hoisting cable 9 and hook 20 relative to mast 1. Thus the hoisting may be accomplished when the latch 16 is engaged on the end of the boom 2; the latch then released 70 by hand by means of rope 19 and the loaded material will then be slid inward toward the mast 1 since ring 15 is slidably mounted on boom 2. The boom itself may be adjusted to the desired height by means of the cable 80 6. The boom being pivotally mounted on the adjustable clamp 3 by means of eyes 22 can be swung laterally in either direction to the extent desired, as indicated in Fig. 2 of the drawings. 85

What I claim is:—

1. In a hay loader, the combination of a mast, a loose clamp mounted on the mast, a boom swingably attached to said clamp, means for vertically adjusting the boom, a 90 hay loading cable, guide pulleys mounted on the mast over which said cable is run, a ring slidably mounted on the boom, a guide pulley suspended from said ring, a latch device carried by the aforesaid ring and 95 normally engaging the end of the boom, and means for manually disengaging said latch member from the end of the boom.

2. In a hay loader, the combination of a mast, a boom vertically adjustable on said 100 mast, means for vertically adjusting the boom, means permitting of lateral swinging movement of the boom, a ring slidably mounted on the boom, a latch member carried by said ring and normally engaging the 105 end of the boom, means for manually disengaging said latch member from the end of the boom, a guide pulley suspended from the ring, a hay loading cable threaded over said guide pulley, and guide pulleys posi- 110

tioned near the upper and lower ends of the mast, respectively, over which the hay-loading cable is threaded.

3. In a hay loader, the combination of a mast, a boom vertically adjustable on said mast, means for vertically adjusting the boom, means permitting of lateral swinging movement of the boom, a ring slidably mounted on the boom, a latch member carried by said ring and normally engaging the end of the boom, means for manually disengaging said latch member from the end of the boom, a guide pulley suspended from the ring, a hay loading cable threaded over said guide pulley, guide pulleys positioned near the upper and lower ends of the mast, respectively, over which the hay-loading cable is threaded, and means for adjustably

clamping said guide pulleys in the desired position on the mast.

4. In a hay loader, the combination of a mast, a boom, means for adjustably mounting the boom on the mast, said means including a plurality of cables attached to the boom near its outer end and near its central portion, a guide pulley adjustably suspended from the boom, means for releasably securing said guide pulley in a predetermined position near the outer end of the boom, guide pulleys clamped near the upper and lower ends of the mast, a hay-loading cable threaded over the aforesaid guide pulleys, and means for securing the mast in erect position.

GEORGE A. PENNOYER.
